UNITED STATES PATENT OFFICE.

JAMES E. RORK, OF KALAMAZOO, MICHIGAN.

ELECTRICAL CONNECTOR.

1,271,226.

Specification of Letters Patent.

Patented July 2, 1918.

Application filed June 18, 1917. Serial No. 175,387.

To all whom it may concern:

Be it known that I, JAMES E. RORK, a citizen of the United States, residing at Kalamazoo, Michigan, have invented certain new and useful Improvements in Electrical Connectors, of which the following is a specification.

This invention relates to electrical connectors.

10 The object of the invention is to provide a flexible connector provided with terminals of such a structure that they may be applied or secured to other terminals of a variety of different shapes.

15 Other objects and objects relating to details and economies of construction and operation will definitely appear from the detailed description to follow.

I accomplish the objects of my invention 20 by the devices and means described in the following specification. The invention is clearly defined and pointed out in the claims.

A structure constituting a preferred embodiment of my invention is illustrated in 25 the accompanying drawings forming a part of this specification, in which:

Figure I shows a flexible cable, the ends of which are provided with my improved terminal.

30 Fig. II is a perspective view showing one use of my improved connector in combination with a battery of storage cells.

Fig. III shows my improved terminal attached to a storage battery terminal of the 35 taper pin type.

Fig. IV shows my improved terminal connected to a cell post.

Fig. V illustrates the means and the method by which my terminal is connected 40 to a flexible cable.

Fig. VI is a plan view of the halves of the mold I employ in making the connection between my improved terminal and the flexible cable.

45 In the drawings similar reference characters refer to similar parts throughout the several views.

Referring to the drawings, the reference character 1 indicates a flexible cable comprising a conducting wire 2 which may, if desired, be of a stranded type and provided with an insulating cover 3.

50 The terminals which are attached to each end of the cable are formed from hard drawn brass wire or any other wire having similar characteristics. The terminal is formed

from a piece of such wire which is coiled at approximately the middle point thereof to form a plurality of juxtaposed coils 4 with the ends of the coil extending from opposite ends thereof, preferably but not necessarily in spaced substantially parallel relation, as shown in Fig. I, where the hooked end of the wire is shown in dotted outline in substantially spaced parallel relation to 65 the shank portion 5 of the terminal. The opposite end of the wire forming the terminal is provided with a hook 6 which is adapted to be engaged with the shank portion 5 of the terminal, as shown in various of the 70 figures.

The ends of the cable 1 are secured to the ends of the shank 5 by twisting the two together as shown at 7 in Fig. V. The two reversely formed complementary molds 8 are 75 then placed about the joint thus formed, as shown in Fig. V. The notches 10 and 10' in the ends of the molds form apertures for receiving the cable 1 and the shank 5 while the opposed notches 9 form an aperture 80 through which the lead may be poured to form the sleeve 11 having the reduced portion 12. This lead sleeve not only increases the conductivity of the joint but it also serves to protect these joints from the injurious 85 effect of acids such as are used in storage batteries, and it also provides a sort of a handle for manipulating the terminal.

In Fig. II, a pair of my improved connectors are shown connecting the charging 90 wires 13 with the terminal wires 14 of a storage battery, the insulation being stripped back from the ends of all of the wires to expose the conductor. All that is necessary to connect one of the terminals to 95 a wire is to force the end of the wire between the adjacent coils or convolutions, the tension of the coils being sufficient to hold them upon the wire or conductor and to give the necessary contact.

In Fig. III, my improved terminal is shown attached to the sleeve of a pin terminal. In making this connection, the hooked end of the terminal is threaded through the opening in the pin terminal and then 105 hooked over the shank 5 whereby the tension of the spring coil is increased to maintain a firm contact between the two terminals.

In Fig. IV, my improved terminal is 110 shown engaged with an ordinary post terminal of a storage cell.

From the above illustration of various uses of my invention, it will be apparent that my improved terminal can be used to make connections with terminals of types other than those illustrated.

Having thus described my invention, what I claim as new and desire to secure by Letters Patent is:

1. In a structure of the class described, 10 the combination with a flexible cable, of a terminal secured to each end thereof comprising a coil of wire formed with a plurality of convolutions and having its ends extended in spaced substantially parallel 15 relation, one of its ends being provided with a hook, the other end forming a shank joined to one end of said cable, and a lead sleeve surrounding the joint between said cable and said shank and extending along said 20 cable and said shank whereby it forms a handle for manipulating said terminal.
2. In a structure of the class described, 25 the combination with a flexible cable, of a terminal secured to each end thereof comprising a coil of wire formed with a plurality of convolutions and having one of its ends provided with a hook, the other end forming a shank joined to one end of said cable, and a lead sleeve surrounding the 30 joint between said cable and said shank and extending along said cable and said shank whereby it forms a handle for manipulating said terminal.
3. In a structure of the class described, 35 the combination with a flexible cable, of a

terminal secured to one end thereof comprising a coil of wire formed with a plurality of convolutions and having one of its ends joined to said flexible cable, the other of said ends being provided with a hook adapted to engage the first named end, and a metal sleeve embedding the joint.

4. In a structure of the class described, 40 a terminal comprising a coil of wire, the ends of said coil extending from opposite sides thereof in spaced substantially parallel relation, one of said ends forming a shank adapted to be connected to a conductor and the other end being provided with a hook adapted to engage said shank, substantially 45 as described.

5. In a structure of the class described, 50 a terminal comprising a coil of wire, one end of which forms a shank adapted to be connected to a conductor and the other end being provided with a hook adapted to engage said shank, substantially as described.

6. In a structure of the class described, 55 a terminal comprising a coil of wire having a pair of adjacent convolutions and extended ends, one of said ends being adapted for engagement with the other end, substantially as described.

In witness whereof, I have hereunto set my hand and seal in the presence of two 60 witnesses.

JAMES E. RORK. [L.S.]
